COLLAR FASTENER

Felix Holzknecht, Vancouver, British Columbia,
Canada, assignor of five per cent to John Morisi,
Washington, D. C.

Application October 15, 1937, Serial No. 169,268

2 Claims. (Cl. 24—101)

This invention relates to a collar fastener and it consists in the constructions, arrangements and combinations herein described and claimed.

It is an object of the invention to provide a 5 collar fastener formed from a single strand of resilient wire shaped to readily conform to a neck band and collar, thereby affording comfort to the wearer and eliminating pressure upon the nerve system of the wearer.

10 It is a further object of the invention to provide a collar fastener in which the securing means consist of resiliently spaced legs thereby eliminating pressures adjacent the spinal column of the wearer.

15 It is a still further object of the invention to provide a fastener which will remain in a substantially single plane with the neck band of a shirt whether the band is of a single or fold-over type, and which will be capable of easy and 20 secure attachment of the collar thereto.

Additional objects, advantages and features of 25 invention will be apparent from the following description and accompanying drawing, wherein,

Figure 1 is an elevational view of the fastener, 25 Figure 2 is a plan view thereof,

Figure 3 is a view of the back of a shirt neck band, a portion being cut away, showing the button hole and the fastener in position,

Figure 4 is a sectional view of a shirt neck band 30 and collar with my fastener applied.

Referring more particularly to the drawing, there is illustrated a fastener generally indicated by the reference character 10 formed from a single strand of resilient wire. The fastener 10 35 comprises an upper portion of wire 11 bent convexly of its length to conform to the annular contour of the band of the shirt indicated at 12. The portion 11 may be of any suitable length and respective ends are given a gradual downward

40 curvature to form side portions 13 and these portions 13 are of a curvature longitudinally, corresponding to the approximate vertical curvature of the collar of the shirt. The portions 13 are of a length approximately three-quarters of the height

45 of the neck band 12 and thence bent as at 14 in an upward direction for a short distance, the latter portion being slightly outwardly inclined as clearly shown in Figure 2 and indicated at 15. Each of the terminal portions of the wire 11 is bent trans-

50 versely a short distance, as indicated at 16 and thence bent downwardly to define offset spaced legs 17 and eyelet 18, the center of respective eyelets lying approximately in a plane parallel to the longitudinal axis of respective side portions 13. The extremity forming the eyelet be-

ing bent in a direction so as to avoid conflict with insertion of the fastener with the button holes of the collar and neck band.

It should be noted that the transverse portions 16 are parallel to the upper portion 11 of the 5 fastener and in use, the bight or bend portion 14 in conjunction with the offset legs 17 form a positive retention of a collar band and collar when engaged in the button holes thereof, due to the resilience of the wire.

In using the fastener, the eyelets 18 are pressed 10 towards each other and are inserted through the button hole in the neck band of a shirt and in final position the upper portion 11 lies parallel to the neck band. When in this position, the bight 15 formed by the transverse portion 16 will hold the upper portion slightly bowed or under tension and thus the legs 17 will be firmly held against the longitudinal extremities of the button hole of the shirt collar. With the fastener in this position, 20 to attach a collar, it is only necessary to open the button hole of the collar sufficiently to admit one of the eyelets 18 therethrough, after which the opposite leg 17 is flexed to admit the other eyelet within the button holes of the collar.

It will be apparent that due to the divergence 25 and inclination of the legs 17 and their inherent resilience the collar will be raised to a point of engagement with the transverse portion 16 and is retained thereby by virtue of the outward resilience of the wire forming the fastener.

Any side strain imposed upon a collar when 30 making adjustment of a tie does not tend to detach the collar from the neck band since any strain involved merely tends to draw one end of a button hole of a collar into tighter engagement with the adjacent transverse portion 16, leaving the legs 17 in engagement with the button hole of the collar.

It will be seen that when in use, the legs 17 35 are spaced apart and will occupy positions upon opposite sides of the spinal column of a wearer, avoiding detrimental pressures to the nerve system.

While I have shown and described a preferred 40 construction this is by way of illustration only and I consider as my own all such modifications in structure as fairly fall within the scope of the appended claims.

I claim:

1. A collar fastener comprising a single piece of 45 resilient wire curved longitudinally and having inwardly inclined side portions, said side portions having an upwardly extended member and a transversely extended member, the latter stop- 50 55

ping short of a vertical axis of the fastener and said transverse member terminating in downwardly extended legs, said legs having closed eyelets, the centers of which lie approximately in a plane parallel to the longitudinal axis of respective side portions.

2. A collar fastener comprising a single piece of resilient wire curved longitudinally and having inwardly inclined side portions, said side portions having an upwardly extended member and a

transversely extended member, the latter stopping short of a vertical axis of the fastener, and said transverse member terminating in downwardly extended legs, said legs being outwardly inclined with respect to the curved portions of the wire, 5 said legs having closed eyelets, the centers of which lie approximately in a plane parallel to the longitudinal axis of respective side portions.

FELIX HOLZKNECHT. 10
